UNITED STATES PATENT OFFICE.

WALTER J. SMART, OF BROOKLYN, NEW YORK, ASSIGNOR TO THE FIRM
OF JOHN WILLIAMS, OF NEW YORK, N. Y.

GAS-BURNER.

SPECIFICATION forming part of Letters Patent No. 690,471, dated January 7, 1902.

Application filed January 30, 1901. Serial No. 45,342. (No model.)

To all whom it may concern:

Be it known that I, WALTER J. SMART, of the borough of Brooklyn, city and State of New York, have invented a certain new and useful Improvement in Gas-Burners, of which the following is a specification.

This invention relates to gas-burners, and particularly to that type or class thereof known as "inverted" gas-burners, and has 10 for an object to provide improved means for delivering a maximum of air to those portions of the flame where combustion can most advantageously occur, whereby increased luminosity or brilliancy is attained.

15 Referring to the drawings which accompany the following specification and illustrate an embodiment of my present invention, Figure 1 is an elevation of such a burner. Fig. 2 is a view of the burner as it appears when 20 looked at from the under side in Fig. 1, and Fig. 3 is a central lengthwise section.

Similar characters of reference designate corresponding parts in all figures.

In the present illustrated embodiment of 25 this invention it is shown applied to an annular burner-body B. The space between the walls 2 and 3 of this annular body communicates with the gas-supply, in the present instance by means of the passages through

30 hollow arms b, (any appropriate number.) As shown, these arms b extend from a socket C, by which the burner may be attached to a gas-outlet toward, and are connected with a ring C', which may be secured gas-tight to 35 the burner-body B in any suitable way. A baffle-plate D, which in the present instance consists of a perforated ring or any other device designed for the purpose of distributing the gas uniformly through the gas-space, may 40 be inserted therein.

The gas-outlet from the burner-body B may consist, as shown, of a number of openings 4, extending through the base thereof and yielding a flame when in use annular in form 45 and curving upward exteriorly of the body. The air-supply to the inside of the flame takes place downward in this form of inverted burner through the axial opening 5 of the annular burner-body. An air-deflector 6 is arranged adjacent to the openings 4. With 50 the form of burner-body shown an effective

shape for this deflector is circular, and preferably the inner wall 2 of the burner-body is chamfered off or beveled from within outwardly toward the openings 4 (see 7) to facilitate the passage of air to the base of the flame as it is directed outwardly by the surface of the deflector 6.

For the purpose of securing as uniform a distribution as possible of air for combustion 60 to all portions of the annular flame this deflector 6 may be supported in position from the burner-body B by means of an air-distributer 8, here shown to be cylindrical in form and of less diameter than the diameter of 65 the axial opening through the burner-body. The perforations in this air-distributer, in view of the function it performs, are spaced substantially uniformly throughout the shell thereof, while the distributer at its lower extremity is attached to the deflector 6, adjacent to the inner edge of the latter. An outwardly-extending flange 9 connects the air-distributer to the burner-body B. This flange 9 is shown perforated also to admit air into 70 the annular space between the distributer and the inner wall 2 of the burner-body, while a shoulder 10 may be provided upon the burner-body to assist in the correct positioning of the parts in place.

80 To secure an efficient delivery of air to the flame at points adjacent to and beyond the base thereof, there may be a second air-distributer attached to the deflector 6, which may consist, as herein illustrated, of a cup-shaped distributer E, comprising a perforated flange dependent from the outer edge of the deflector 6 and a perforated disk 12 at the lower portion of this dependent flange.

85 Combined and organized in the manner 90 illustrated and described, a burner of the foregoing-characterized type is provided with means for directing the incoming air to those portions of the flame at which it is most effective in increasing the brilliancy of the 95 light, as well as means for dividing up and rendering uniform the distribution not only to those portions, but the surplus air for combustion to other portions of the flame.

Having described my invention, I claim— 100

1. An annular air-deflector combined with a cylindrical air-distributer on one side of the

deflector, and an air-distributer on the other side thereof disposed adjacent to the outer edge of the deflector.

2. An annular deflector combined with a cylindrical air-distributer on one side of the deflector, and a cup-shaped air-distributer on the other side thereof consisting of a perforated flange extending from the outer edge of the deflector and a perforated disk at the end 10 of the flange.

3. An annular deflector combined with a cylindrical air-distributer on one side of the deflector, a perforated flange extending from the cylindrical air-distributer and a cup-shaped air-distributer disposed on the opposite side of the air-deflector and consisting of a perforated flange extending from the outer edge of the deflector and a perforated disk at the end of the flange.

20 4. In combination with an annular burner-body, an annular air-deflector, a cylindrical air-distributer on one side of said deflector, and an air-distributer on the other side thereof disposed adjacent to the outer edge of the 25 deflector.

5. The combination with an annular burner-body having its inner wall chamfered or beveled adjacent to the burner-outlet, of an air-deflector located centrally of the burner-body

and in proximity to the chamfered portion of 30 the wall of the body and an air-distributer.

6. In combination with an annular burner-body having its inner wall chamfered or beveled adjacent to the burner-outlet, of an air-deflector, an air-distributer on one side of 35 the deflector and an air-distributer on the other side thereof.

7. In combination with an annular burner-body having its inner wall chamfered or beveled adjacent to the burner-outlet, of an air-deflector, a cylindrical air-distributer on one side of the deflector and a cup-shaped air-distributer on the other side thereof. 40

8. In combination with an annular burner-body having its inner wall chamfered or beveled adjacent to the burner-outlet, of an annular air-deflector, a cylindrical air-distributer on one side of the deflector, a cup-shaped air-distributer on the other side thereof, and a flange connecting the cylindrical air-distributer with the burner-body. 45

In testimony whereof I have hereunto signed my name in the presence of two subscribing witnesses.

WALTER J. SMART.
